UNITED STATES PATENT OFFICE.

LESTER HOLTON ALLEN, OF FARMINGTON, N. H., ASSIGNEE, BY MESNE ASSIGNMENTS, TO HIMSELF AND ALONZO I. NUTE, OF SAME PLACE.

MACHINERY FOR FINISHING BOOT-LEGS, &c.

SPECIFICATION forming part of Letters Patent No. 284,265, dated September 4, 1883.

Application filed May 22, 1883. (No model.)

To all whom it may concern:

Be it known that I, LESTER HOLTON ALLEN, of Farmington, in the county of Strafford, of the State of New Hampshire, have invented a new and useful Improvement in Machinery for Finishing Boot-Leg or various other Seams; and I do hereby declare the same to be described in the following specification and represented in the accompanying drawings, of

10 which—
Figure 1 is a top view, and Fig. 2 a side elevation, of a machine embodying my invention, the nature of which is defined in the claim hereinafter presented. Figs. 3 and 4 are vertical sections of the boxes and the supports thereof of the upper worm-shaft, to be herein-after described. Fig. 5 is an edge view of the two finishing-rollers.

In this machine the seam to be flattened and 20 rubbed down or finished is to be run between two rollers, A and B, the upper of which is concave and the lower convex across its periphery, as represented. The upper roller has a diameter about half that of the lower one, 25 the latter being pivoted within a stationary arm, C, projecting, as shown, from a standard, D. Another such arm, E, also extends from the standard, and is arranged over the arm C in manner as represented. There is 30 fixed on the pivotal shaft s of the roller B a worm-gear, a, that engages with a worm or screw, b, fixed on a horizontal shaft, c, ar- 35 ranged as shown, and supported in boxes d d, projecting from the standard D and arm C. A gear, e, fixed on the shaft c, engages with another gear, f, fixed on a driving-shaft, g, supported in boxes h h, projecting from the standard. A driving-wheel, i, revolves freely 40 on the said shaft, except when clutched there- to, such wheel and shaft being provided with a suitable clutch. The gear f, that engages with a pinion, k, carried by the upper worm-shaft, l, is provided at its outer end with a worm or screw, m, that engages with a worm-gear, n, 45 fixed on the shaft n' of the upper roller, A. The said shaft n' is journaled in the shorter arm of a lever, F, which is fulcrumed to the arm E, and extends in front of and over such arm in manner as represented. The longer 50 arm of the lever F rests on a spiral spring, G,

supported on the arm E. Any other proper kind of a spring may be used in the place of the said spiral spring to force the said longer arm upward, in order to press the upper roller, A, downward relatively to the roller B. 55

As a boot-leg seam to be flattened and rubbed down or finished will vary more or less in thickness, and as the seam of one boot-leg may also vary in thickness relatively to that of another to be finished by the machine, it will be 60 seen that in passing between the rollers A and B the upper of such rollers will necessarily have a movement more or less upward and downward.

In order that the worm m may maintain its 65 due relations to the gear n, or move upward and downward therewith to keep properly in engagement with it, there is combined with the worm-shaft and the arm E and the lever F a peculiar mechanism, which may be thus 70 described: A lever, H, fulcrumed to a stand- 75 ard, o, extending upward from the arm E, and arranged therewith as shown, has its longer arm pivoted to that of the lever F. The shorter arm of such lever H is jointed to a slide, I, 80 adapted to move upward and downward in a bracket, p, extending from the arm E. Within this slide I, and pivoted to it, is one of the boxes q r of the shaft l, the other of said boxes being suitably pivoted in a bracket, s', extend- 85 ing from the standard D, the whole being so as to enable the worm of the shaft l to move upward and downward with the gear with which it engages. The roller A, in rising relatively to the roller B, will move the lever F, 85 so as to cause the longer arm thereof to de- 90 scend and force downward that of the lever H, whereby the slide I will be pulled upward, so as to cause the worm-shaft and its worm to rise with the worm-gear of the roller A. The 90 said upper roller revolves faster than the lower roller, and consequently when the boot-leg seam is between the two rollers such seam will not only be flattened or compressed by them, but will be rubbed and finished by the upper 95 roller.

In practice the machine has been found to operate to excellent advantage. When the machine is in use, the lever F is connected to a foot-treadle on the floor by means of a rod 100

attached to the rear end of the lever F, such being for the purpose of raising the upper roll, A, by the foot at the will of the operator. This is to remove the work at any time without running it through the machine. When, in the place of the spiral spring G, I use a bow or leaf spring to force the longer arm of the lever F upward, I have a screw screwed down through the arm near the free end of the spring, such screw being to bear against the spring to vary the upward pressure of it, as occasion may require, such spring being fastened to the arm E.

In the seam-finishing machine as explained,
15 I claim—

In combination with two rollers, A and B,

and their mechanism, as described, for revolving them at different rates of speed, and with the pressure spring and lever, of the upper of said rollers, mechanism, substantially as set forth, for causing the actuating-worm of the upper roller to rise and fall in unison with the gear in engagement with it, and fixed on the shaft of the said roller, such mechanism consisting of the lever H, the slide I, and the two pivoted boxes qr, all being arranged and adapted essentially in manner and to operate as represented.

LESTER HOLTON ALLEN.
